US00D810802S

(12) **United States Design Patent** (10) **Patent No.:** **US D810,802 S**
(45) **Date of Patent:** **** Feb. 20, 2018**

(54) **CAMERA**

(71) Applicant: **VITRONIC Dr.-Ing. Stein
Bildverarbeitungssysteme GmbH,
Wiesbaden (DE)**

(72) Inventor: **Andreas Schulze, Hunfelden (DE)**

(73) Assignee: **VITRONIC Dr.-Ing. Stein
Bildverarbeitungssysteme GmbH,
Wiesbaden (DE)**

(**) Term: **15 Years**

(21) Appl. No.: **29/575,479**

(22) Filed: **Aug. 25, 2016**

(30) **Foreign Application Priority Data**

Feb. 25, 2016 (EM) 003001460-0001

(51) **LOC (11) Cl.** **16-01**

(57) **CLAIM**

The ornamental design for a camera, as shown and described.

DESCRIPTION

FIG. 1 is a front view of a camera showing our new design;

FIG. 2 is a top view thereof;

FIG. 3 is a bottom view thereof;

FIG. 4 is a right side view thereof;

FIG. 5 is a front, right perspective view thereof;

FIG. 6 is a rear, right perspective view thereof; and,

FIG. 7 is a front, left, bottom perspective view thereof.

The broken lines shown in the drawings depict portions of

the camera that do not form part of the claimed design.

1 Claim, 7 Drawing Sheets
